CLAIM

The ornamental design for a lid for a blender, as shown and described.

DESCRIPTION

FIG. 1 is a perspective view taken from the top right and right side, illustrating our design of a lid for a blender; FIG. 2 is an elevation view thereof taken from the right side as viewed in FIG. 1;

FIG. 3 is an elevation view of our new design taken from the left side as viewed in FIG. 1;

FIG. 4 is an elevation view of our new design taken from the rear as viewed in FIG. 1;

FIG. 5 is a top plan view of our new design; and,

FIG. 6 is a bottom plan view thereof.
